UNITED STATES PATENT OFFICE.

JOHN B. LOCKER, OF ST. LOUIS, MISSOURI.

ALARM.

1,421,267.

Specification of Letters Patent. Patented June 27, 1922.

Application filed July 12, 1921. Serial No. 484,128.

To all whom it may concern:

Be it known that I, JOHN B. LOCKER, a citizen of the United States, residing at St. Louis, in the county of St. Louis City and State of Missouri, have invented new and useful Improvements in Alarms, of which the following is a specification.

The invention relates to improvements in signalling devices and particularly to 10 that class of devices utilized for sounding an alarm, the invention being especially useful in the class of devices known as burglar alarms.

An object of the invention is the provision of a device of the above character which may be secured to a door or window and automatically operated by the opening of said door or window to explode a cartridge, torpedo or other explosive, so as to give 20 warning of the unauthorized opening of the said door or window. The invention is further susceptible of use as a circuit closer for sounding a bell or lighting a lamp, or both.

25 Another object of the invention is the provision of means whereby the devices may be rendered inactive, so that the door or window to which it is secured, may be opened without operating the alarm.

30 Other objects and advantages of the invention will appear as the following description is read in connection with the accompanying drawings.

In the drawings:

35 Figure 1 is an elevation showing a portion of the inside of a door with the latter closed and the invention set in position for use.

Figure 2 is a similar view showing the 40 device after operation.

Figure 3 is a like view locked against operation.

Figure 4 is a section on the line 4—4 of Figure 1.

45 Figure 5 is a view looking at the lower end of the device with the parts in the position shown in Figure 1 and the anvil block broken away.

Figure 6 is an enlarged sectional view on 50 the line 6—6 of Figure 1.

Figure 7 is a fragmentary section illustrating means for holding the hammer against operation.

Figure 8 is an elevation showing a type 55 of locking device which may be used in connection with the invention.

Referring in detail to the drawings, wherein like characters of reference denote corresponding parts, the reference character 10 indicates a portion of a door, the 60 frame or jamb of which is indicated at 11.

The invention comprises a frame which is preferably of triangular shape, the base of which forms a guide arm 12 while the hypotenuse of the triangle forms a hammer 65 arm 13 and the altitude of the triangle, a connecting means between the guide arm and hammer arm, the connecting means being indicated at 14. The frame is preferably formed of resilient wire and the outer end of 70 the guide arm 12 is pivotally secured within a block 15 which forms an anvil and serves as a connection between the frame and the door upon which it is mounted.

Slidingly mounted upon the guide arm 75 12 is a hammer block, 16, the latter being provided with an opening for the reception of the guide arm 12, while extending through the hammer block is an additional opening which receives the free end of the 80 hammer arm 13 so that the latter forms a spring to actuate the hammer block. To increase the spring action of the hammer arm 13, the frame is provided with a coil 17 at the juncture of the hammer arm with 85 the connecting means or rod 14. The anvil block is provided with a socket 18 which is adapted to receive a cartridge, torpedo or other explosive element and this socket is so located as to be in the path of movement 90 of the hammer block 16 so that when the latter is actuated by the hammer arm, the said explosive element will sound the alarm.

The frame is designed to be mounted upon the inside of a door and for this purpose 95 there is provided a stem 19 which is secured to the anvil block and which rotates within a locking device 20 which extends through the door 10. This locking device is designed to be controlled by a key and for 100 this purpose there is provided a key slot 21. Normally the anvil block is positioned so that the hammer block will contact with the cartridge or other element located within the socket 18 but if desired the anvil block may be rotated through the use of a 105 suitable key so as to position the explosive element out of the path of the hammer block. When so arranged the hammer block will contact with a cushioning or insulating 110 member 22 which is carried by the anvil block.

In order to set the device there is provided a pair of triggers 23. Each of these triggers includes a loop 24 which is secured upon the connecting rod 14 within a loop 25 provided for that purpose so that the triggers 23 are substantially pivotally mounted within this loop 25. Each of the triggers 23 in addition to the loop includes a hook arm 26 and a finger 27, the hook arm 10 of each of the triggers being reversely arranged so as to receive between them the hammer arm 13. The fingers 27 are arranged substantially at right angles to the hook arms 25 and are designed to be secured 15 between the edge of the door 10 and the frame 11 so as to be held against movement. The hammer arm 13 will thus be securely held between the outer ends of the hook arms until the door is opened, which opening will permit the fingers 27 to move so as to release the hammer arm 13 and cause the hammer to travel along the guide arm 12 for contact with the explosive element.

If desired the frame may be constructed 25 from a single piece of spring wire, or may be formed of separate sections and connected by forming one section with an eye 28 which is received within the loop 25 while the extremity of the connecting rod 30 14 and the adjacent portion of the guide arm 12 are surrounded by a binding loop 29.

Additional means may be provided for holding the hammer against operation when the anvil block is rotated to move the explosive element out of the path of said hammer block. This means comprises an arm 30 having one end pivotally secured within an eye 31 extending through the anvil block. The opposite end of this arm is formed with 40 a hook 32 which engages over the fingers 27 of the triggers so as to hold them against outward movement and prevent the release of the hammer arm.

In addition to the use of the invention as 45 above described, the device may be used for closing a circuit to sound an alarm or light a lamp. For this purpose the anvil block and hammer block may be connected in circuit with the signals and suitably insulated 50 from the remainder of the device. Thus when the device is operated the circuit will be closed, as will be readily understood.

The invention is susceptible of various 55 changes in its form, proportions and minor details of construction and the right is herein reserved to make such changes as properly fall within the scope of the appended claims.

Having described the invention what is 60 claimed is:—

1. A signalling device comprising a frame, means whereby said frame may be secured to a movable member, an anvil secured to the frame, means for holding an explosive element upon the anvil, a spring actuated

hammer movable upon the frame, means carried by the frame for holding the hammer against movement and means included in the hammer holding means for engagement between the movable member and a stationary member to hold the hammer against operation. 70

2. A signalling device comprising a frame, means whereby said frame may be secured to a movable member, an anvil secured to the frame, means for holding an explosive element upon the anvil, a hammer movable upon the frame, a spring actuated hammer arm included in said frame for operating the hammer, means carried by the frame for holding the hammer against movement and means included in the hammer holding means for engagement between the movable member and a stationary member to hold the hammer against operation. 80

3. A signalling device comprising a frame, means whereby said frame may be secured to a movable member, an anvil secured to the frame, means for holding an explosive element upon the anvil, a hammer movable upon the frame, a spring actuated hammer arm included in said frame for operating the hammer, oppositely movable triggers carried by the frame and engageable with the hammer arm for holding the hammer against movement and means included in the triggers for engagement between the movable member and a stationary member to hold the hammer against operation. 90

4. A signalling device comprising a frame, means whereby said frame may be secured to a movable member, an anvil secured to the frame, means for holding an explosive element upon the anvil, a spring actuated hammer movable upon the frame, means carried by the frame for holding the hammer against movement, means included in the hammer holding means for engagement between the movable member and a stationary member to hold the hammer against operation and means whereby the anvil may be moved to move the explosive element out of the path of the hammer. 100

5. A signalling device comprising a frame, means whereby said frame may be secured to a movable member, an anvil secured to the frame, means for holding an explosive element upon the anvil, a spring actuated hammer movable upon the frame, means carried by the frame for holding the hammer against movement, means included in the hammer holding means for engagement between the movable member and a stationary member to hold the hammer against operation and key controlled means whereby the anvil may be moved to move the explosive element out of the path of the hammer. 115

6. A signalling device comprising a frame, means whereby said frame may be

secured to a movable member, an anvil secured to the frame, means for holding an explosive element upon the anvil, a spring actuated hammer movable upon the frame, 5 means carried by the frame for holding the hammer against movement, means included in the hammer holding means for engagement between the movable member and a stationary member to hold the hammer 10 against operation, key controlled means whereby the anvil may be moved to move the explosive element out of the path of the hammer and means controlled by the position of the anvil for engagement with 15 the triggers to prevent operation of the hammer.

7. A signalling device comprising a frame, means whereby said frame may be secured to a movable member, an anvil secured to the frame, means for holding an explosive element upon the anvil, a spring actuated hammer movable upon the frame, 20 means carried by the frame for holding the hammer against movement, means included

in the hammer holding means for engagement between the movable member and a stationary member to hold the hammer against operation, key controlled means whereby the anvil may be moved to move the explosive element out of the path of the hammer and a trigger engaging arm pivotally secured to the anvil for preventing 25 30 35 operation of the hammer.

8. A signalling device comprising a triangular frame, an anvil located at one corner of the frame, means for holding an explosive element upon the anvil, means whereby the frame may be secured in position, a hammer slidably mounted upon the base of the frame, a spring arm included in the frame and engageable with the hammer for operating the latter and a trigger carried by the frame and engageable with the spring arm and between a movable and a stationary member for holding 40 45 the hammer against movement.

In testimony whereof I affix my signature.
JOHN B. LOCKER.
